UNITED STATES PATENT OFFICE

WILLIAM E. WHITE, OF CHICAGO, ILLINOIS, ASSIGNOR TO KALMAN STEEL COMPANY,
OF CHICAGO, ILLINOIS, A CORPORATION OF DELAWARE

ROAD STRIP AND SUPPORT

Application filed April 23, 1928. Serial No. 272,132.

My invention relates to concrete roads and particularly to novel means for positioning and supporting a narrow strip constituting a joint in said roadway.

It is customary with some builders of roads to mount a narrow strip of metal along the line of an expansion joint in the monolithic roadway and then, after the cementitious material has partially set, to withdraw the strip and to place therein an impregnated felt strip.

Inasmuch as the sole purpose of the strip under any circumstances is to provide an expansion joint I have conceived the idea that the desired result may be accomplished with equal facility by utilizing a relatively very light section of metal extending through only a portion of the depth of the pavement and allowing the strip to remain in the concrete. This involves certain equipment and the performance of certain essential steps, examples of which will be disclosed herein.

Suitable stakes or similar supports, intended to become a permanent part of the roadway are essential regardless of the type or character of the material of the strip and these stakes must be accurately aligned and positioned under any circumstances. My invention comprises a novel form of stake, strip and fastening clip, the construction of which will be fully described herein.

My invention will be more readily understood by reference to the accompanying drawings, in which—

Fig. 1 is a perspective view of a stake, strip, fastening clip and dowel bar;

Fig. 2 is a side elevation thereof with a bar in section; and

Fig. 3 is a view of a slightly modified form of the invention.

In the drawings, I have illustrated a stake 10 which may be of angular or channel cross section having a head or flat portion 11 that overlies and preferably rests upon the side flanges of the stake. At the sides of the head 11 are right angularly disposed, up-standing lugs 12, spaced apart sufficiently to accommodate the flange 13, of the road strip 14. The latter may be of relatively thin metal

and is intended to be allowed to remain in the finished roadway.

The flange 13 of the strip rests on the head 11 between the lugs 12 and is held firmly in proper position by means of a sheet metal clip and bar support. The clip is in a form of a strip of sheet metal bent into angular form having a flat portion 14 and a down turned end 15. An aperture 16 extends into both said portions 14 and 15. The part of the aperture located in the portion 15 acts as a socket or seat for the dowel bar 13 while the part of the aperture 16 in the part 14 cooperates with the lug 12. The clip also has a vertical portion 18 adapted to lie against the web 14 of the strip, and a rebent horizontal end 19 adapted to be firmly held between the top of the lug 12 and the web 14. The parts are so dimensioned that when the strip is laid on the head of the stake, the clip may be dropped into place and by a hammer blow firmly held by friction in the position shown in the drawings. After the bar 17 is positioned as shown the clip cannot escape by upward movement and the parts are fully interlocked.

In the construction shown in Fig. 3 the stake 20, strip 21 and strip flange 22 are substantially identical with those already described. However, the lugs 23 on the stake head are provided with oppositely inwardly formed notches 24 near the bottom of the space between the lugs. These are provided to accommodate the clip which is of Z shape in cross section. It comprises the bottom flange 25 adapted to enter the notches 24, the web portion 26, and the upper flange 27, adapted to abut the web 21. After the strip and stake have been associated the clip is dropped into place and a hammer blow firmly seats it, thereby interlocking the parts and preventing upward movement of the strip relative to the stake.

Other modifications and variations may be made in the invention and I do not wish to be limited except as indicated in the appended claims.

I claim:

1. In combination, a relatively narrow elongated strip having a flange at its lower edge, a stake having a head, means on the

head for defining a seat to receive the flange and a clip engaging said seat defining means and said strip for retaining the strip and stake against relative vertical movement.

5. 2. In combination, a road strip having a bottom flange, a stake having a head, lugs projecting upwardly from the head and defining a space adapted to receive the bottom flange of the strip and a metal clip adapted to be seated above the flange and to hold the strip and stake against relative vertical movement.

10. 3. In combination, a strip, a stake having a seat, and upwardly projecting lugs therefrom between which lugs said strip is adapted to be held, a clip adapted to engage said strip and one of said lugs to hold the strip and stake against relative vertical movement.

15. 4. In combination, a strip, a stake having a seat, and upwardly projecting lugs therefrom between which lugs said strip is adapted to be held, a clip adapted to engage said strip and one of said lugs to hold the strip and 20 stake against relatively vertical movement, said clip having an apertured portion adapted to accommodate a dowel bar passing beneath the plane of the seat on the stake.

25. 5. In road construction, in combination, a strip of less depth than the thickness of the pavement, a stake having a head, a pair of lugs projecting upwardly from the head and defining a strip receiving recess, a sheet metal clip adapted to occupy the space between the 30 strip and one of said lugs, said clip having an apertured depending portion adapted to receive a transverse dowel bar.

35. 6. In road construction, in combination, a narrow metal strip having a bottom flange, a stake having a flat head provided with standing lugs defining a space therebetween shaped to accommodate the flange on said strip, a keeper held between one of said lugs and said strip and resting on the flange on 40 said strip, said keeper having a depending portion adapted to receive a transverse bar extending beneath said strip.

In testimony whereof I have affixed my signature.

WILLIAM E. WHITE.
